BREECH BOLT RETRACTING MEANS

Frederick W. Sampson, Dayton, Ohio, and George J. Hyde, Brooklyn, N. Y., assignors to General Motors Corporation, a corporation of Delaware

Application May 1, 1944, Serial No. 533,568

4 Claims. (Cl. 42—16)

1

This invention relates to an improved breech retracting means for a firearm having a reciprocating breech member and more particularly to such means suitable for application to a firearm of the type commonly referred to as a submachine gun or machine pistol.

It is the primary object of this invention to produce a dependable breech retracting means which does not partake of movement of the breech member during automatic fire and does not therefore have any exposed moving parts which might injure hands or clothing or detract from the efficiency of the weapon's operation in confined spaces or in heavy undergrowth.

It is a further object to provide a breech retracting system for firearms which may be mounted and which can be operated without necessitating the provision of openings or slots in the wall of the firearm which can be obstructed by dirt or foreign material.

The exact nature of the invention as well as other objects and advantages thereof will be clearly apparent from an examination of the following specification referring to the annexed drawing in which:

Fig. 1 is a partial, longitudinal sectional view through a firearm embodying our invention;

Figs. 2 and 3 are partial longitudinal sectional views taken in the same plane as Fig. 1 but showing the mechanism in different stages of operation;

Fig. 4 is an exploded pictorial view of the parts making up the cocking mechanism;

Fig. 5 is a cross sectional view on the line 5—5 of Fig. 1.

Fig. 6 is a cross-sectional view on line 6—6 of Fig. 1.

Referring to the drawing by characters of reference it will be seen that the firearm shown therein is of the same general type as that disclosed in our copending applications for U. S. Letters Patent bearing Serial Nos. 533,566; 533,567; 533,569 and 533,570, filed May 1, 1944, in which the structure disclosed but not claimed in this application is claimed, and comprises a receiver 1 having mounted therein a reciprocating bolt 10. The construction shown herein mounts the bolt 10 on spaced guide rods 15 surrounded by driving springs 17 which impel the bolt forwardly into battery position. The particular retracting means to be described hereinafter is not however limited to this construction as it is applicable to the problem of retracting any reciprocating member.

A drawn sheet metal housing 44 is shaped to con-

form to the exterior contour of the receiver and is provided at its front end with a tongue 45 engaging a slot in the magazine housing 3 and at its rear end with a tongue 46 engaging a slot in the lower portion of the receiver. Matching apertures 47 and 48 are provided in the housing 44 and in that portion of the receiver opposed thereto. The trigger guard 49 is formed of resilient material and is provided with shoulders 49a which will not pass through the matching apertures 47 and 48 and with an arched tongue 50 which does pass through the apertures into contact with the inner wall of the receiver. It will be apparent that when the trigger guard is bent upwardly against its own resiliency into a position in which the tongue 50 may snap into an aperture 2a in the grip portion of the receiver that the housing will be securely retained in place. It will be noted that the side walls of the housing overlap the side walls of the receiver and that the lower housing forms a complete closure for the openings in the lower portion of the receiver. In addition to serving as a closure for the lower part of the receiver the housing forms a support for the retracting mechanism, to be described in detail below and the ejector 52 which is riveted or otherwise secured thereto and extends upwardly into a position to be received in a groove 53 in the bolt in position to engage the head of a cartridge gripped by the extractor and impel same upwardly and to the right as the bolt recoils upon firing. A stop tongue 54, cooperating with the retracting mechanism in a manner to be described hereinafter, is cut from the rear edge of the ejector and turned inwardly across the housing.

A breech retracting handle 55 is provided with an axle 55a pivotally mounted in the lower portion of the housing 44. Within the housing a portion of the axle is flattened and carries thereon a torsion spring 56 and a retracting lever arm 57 which so engages the flattened portion of the axle that it is constrained to rotate therewith, and under the influence of the spring 56 both the handle and the retracting lever arm tend to swing forwardly in the direction of the magazine housing 3 until such motion is restrained by contact of the lever arm with the bottom wall of the housing 44.

A retracting pawl 58 is pivotally supported on the end of the retracting lever arm and a pawl spring 59 is provided tending to swing the pawl upwardly into a direction substantially in prolongation of the lever arm. This tendency is, however, limited by the presence of a stop 60 near the end of the retracting lever arm 57 which is

in position to engage the heel 61 of the pawl and prevent damage to the spring in the event of displacement of the retracting handle from its idle position during intervals when the housing may have been removed from the receiver. It will also be noted that the heel of the pawl engages the arched cam surface 44a as the retracting lever arm nears its forward position, thus rocking the pawl downwardly and to the rear about its pivot. Obviously in order to accomplish this result the spring 56 will have to be capable of exerting greater force than the spring 59. This camming action positively removes the pawl from the path of the bolt during automatic operation of the arm. The tongue 54 on the ejector extends across the path of the pawl and aids the cam surface 44a in removing the pawl from the path of the bolt and in preventing the pawl from assuming a position in which improper assembly might be possible when the housing is attached to the receiver.

As the retracting handle is swung rearwardly against the action of the spring 56 the spring 59 will urge the pawl upwardly into the groove 62 in the lower face of the bolt and into a position in which the toe 63 of the pawl engages a depression 64 in the rear end of the groove. Further retraction of the handle will result in carrying the bolt rearwardly with the pawl into a position in which the sear 26 engages and retains the bolt. Releasing the retracting handle will permit the handle, lever arm, and pawl to return to their inactive forward position in which there is no connection with the bolt and in which position the cocking mechanism may remain until such time as it is again necessary to cock the mechanism manually.

It will be noted that the mechanism shown herein does not present any exposed parts which partake of movement of the bolt during automatic fire and that there is therefore no danger that hands or clothing will be injured during automatic fire. At the same time however, there is provided a most convenient cocking handle which by an easy natural movement will engage itself with and cock the mechanism.

It will also be noted that this mechanism functions without requiring the provision of openings, slots, or track guided members which might permit the entrance of dirt into the interior mechanism or which might in themselves be obstructed by dirt or foreign materials.

Although this mechanism finds its greatest utility as a breech retracting means for an automatic firearm it will be obvious that similar means might be applied to the intermittent manual operation of any reciprocating member.

We claim:

1. In a firearm, the combination of a reciprocating firearm member, a lever journaled in the firearm, a pawl member having a pawl portion and an extension portion in longitudinal alignment therewith, means intermediate said portions pivotally mounting said pawl member on said lever, means causing said pawl to engage the firearm member when the lever is actuated in one direction and means engaging said extension portion when said lever is moved in the reverse direction whereby said pawl is drawn clear of the path of the firearm member.

2. A firearm cocking mechanism comprising a housing, a lever journaled in the housing, means to swing the lever, a pawl member having a pawl portion and an extension portion longitudinally in alignment therewith, means intermediate said portions pivotally mounting said pawl member on said lever, a spring abutting said lever tending to bias the same to an idle position, spring means tending to swing the pawl member toward a position in substantial prolongation of the lever, and means on the housing engaging said extension portion as the lever approaches its idle position to cause said pawl portion to assume a pivoted back position on the lever when the lever is in idle position.

3. In a firearm, the combination of a member to be cocked, a housing, a crank, a spindle fixed to the crank and journaled in the housing, a lever arm within the housing and engaging the spindle to be rotated thereby, a spring engaging the housing and the lever arm and tending to bias the crank and the lever arm to a forward idle position, a pawl member having a pawl portion and an extension portion in longitudinal alignment therewith, means intermediate said portions pivotally mounting said pawl member on said lever-arm, spring means engaged between the pawl portion and the lever arm and biasing the pawl member toward a position for engagement with the member to be cocked, and means on the housing engaging said extension portion when the lever is in idle position to hold the pawl portion away from engagement with the member to be cocked.

4. In an automatic firearm, the combination of a reciprocating firing member, a cocking mechanism therefor including a pawl member having a pawl portion and an extension portion in longitudinal alignment therewith, a crank means operatively connected to said pawl member intermediate said pawl portion and said extension portion, means causing said pawl portion to engage said firing member to cock the same when the crank means is moved in a firearm cocking direction, and means arranged to engage said extension portion to remove said pawl portion from the path of said firing member when said crank means is moved in a direction opposite to said cocking direction to a non-operating position.
